UNITED STATES PATENT OFFICE.

FLOYD L. SCOTT AND RALPH NEUHAUS, OF HOUSTON, TEXAS, ASSIGNEES TO HUGHES TOOL COMPANY, OF HOUSTON, TEXAS, A CORPORATION OF TEXAS.

WELL REAMER.

Application filed June 11, 1925. Serial No. 36,540.

Our invention relates to well reamers. It finds application in well drilling and serves to preserve the size of the hole being drilled.

It is an object of the invention to provide a form of construction for well reamers which will be cheap and economical to manufacture and easy and simple to assemble. It is desired to make the tool of a minimum number of parts; which may be assembled and again taken apart with as small a consumption of time as possible.

Referring to the drawing herewith, Fig. 1 is a side view partly in elevation and partly in central longitudinal section. Fig. 2 is a transverse section through Fig. 1 on the plane 2—2 showing one of the sets of reaming cutters removed. Figs. 3 and 4 are side and end elevations respectively of the locking block used to secure the cutter pins in position. Figs. 5 and 6 are side and end views respectively of the removable bearing member. Like numerals of reference are employed to designate like parts in all the views.

In carrying out our invention it is desired to make the device strong and substantial, but simple in construction. We therefore employ a tubular head 1, which is adapted to act as a drill collar as well as a body for the reamer. Its upper end may therefore be threaded internally with a fine thread at 2 for attachment to a section of pipe or drill stem. Its lower end has an outwardly flaring socket 3 coarsely threaded to receive the shank of a drill bit.

The body of the reamer is preferably somewhat elongated so as to enable the reamer to act as a guide to hold the drill straight in the hole and thereby avoid drilling a crooked hole. One or more stages of rolling cutters may be employed and we have shown two. These cutters are arranged in vertical alignment in sets of three. Each cutter is mounted in a radial recess 4, in the side of the head and is preferably in two parts or sections. The upper section 5 is tapered at its upper end but is otherwise of cylindrical outline toothed at 7 to cut the side of the hole. The lower section 6 is cylindrical and toothed. The said sections are mounted rotatably upon an upright bearing pin 8 the ends of which are reduced slightly in diameter. The upper reduced end fits with a socket or recess 9 bored in the upper

wall of the recess 4 to receive it. It is held non-rotatably therein by means of a transverse pin 10 extending through the socket 9 as shown. The lower set of cutters is set in its recess 4' in the same manner as in the case of the upper set except that the tapered section is presented downwardly. The pin 11 is set at its lower end in a socket 9' and has a transverse pin 10' therethrough.

The adjacent ends of the two cutter pins 8 and 11 are secured removably in position by bearing blocks, 12, 12 fitting against the inner sides of the upper and lower pins respectively. These bearing blocks are arcuate in shape, as shown in Fig. 6 and have a recess 14 on the outer side to receive the reduced end of its bearing pin. The locking block 15 is adapted to fit between the two bearing blocks 12, 12. It has its inner face rounded to fit said recess 4, but is spaced normally from the walls of the recess a slight distance to give the block a radial adjustment. The block 15 has upper and lower longitudinal extensions 16 fitting about the adjacent ends of the pins 8 and 11 to hold them in operative position. The locking block is clamped tightly against the cutter pins by set screws 17, which are set at an angle to each other diverging inwardly for engagement in the body of the reamer.

It will be noted that the radial recesses 4 and 4' constitute what is in fact one recess which may be formed in the body of the reamer. The cutters may be assembled in position by placing the cutter sections upon their bearing pins, as shown. Bearing washers at the ends of the cutters may be employed as shown at 18. The outer ends of the pins are then engaged in their sockets 9 and 9' and the bearing blocks 12, 12 placed in position. The locking block 15 is then inserted in position and clamped firmly in locked position against the ends of the pins by the set screws 17. The pressure of the locking block on the cutter pins serves to assist in preventing rotation of the pins.

It will be obvious that a reamer thus formed will be simple and economical to manufacture and will be easy to assemble. The cutters may be changed or repaired without removing the reamer from the drill stem or drill.

Having thus described our invention what we claim as new is:

1. A reamer comprising a unitary tubular body threaded at its ends for engagement to the drill stem and the drill, said body having radial recesses in the sides thereof, upper and lower cutters in each of said recesses, bearing pins for said cutters, bearing blocks for the adjacent ends of said pins, and a locking block fitting between said bearing blocks and having means thereon engaging the ends of said pins to clamp them non-rotatably in their bearings. 35
2. A reamer comprising a tubular body having its ends internally threaded, said body having a plurality of longitudinal radial recesses therein, upper and lower bearing pins in each said recess, removable bearing blocks for the adjacent ends of said pins, a locking block shaped to fit between said bearing blocks and clampingly engage the said adjacent ends of said pins, and cutters on said pins. 40
3. A reamer comprising a tubular body adapted for attachment to a drill stem, said body having radial recesses therein, upper and lower cutter pins having their remote ends received in sockets in the ends of said recess, removable means to clamp the adjacent ends of said pins in position, and cutters rotatable on said pins. 45
- 30 4. A reamer comprising a tubular body, a plurality of cutter pins mounted in vertical alignment in recesses in the sides of said body, the adjacent ends of said pins having removable bearing blocks, locking blocks between said bearing blocks, means on said blocks to clamp the adjacent ends of said pins, and roller cutters on said pins. 50
5. A reamer comprising an approximately cylindrical body with longitudinal recesses in its outer face, each recess adapted to receive a plurality of cutters, cutter pins mounted in each of said recesses, the uppermost and the lowermost of said cutter pins having their remote ends received in the walls of said recesses, cutters on said pins and detachable means to clamp the adjacent ends of said pins in non-rotatable position. 55
6. In a reamer having roller cutters mounted upon cutter pins arranged in vertical stages therein, the improvement comprising a removable locking block secured in position between the adjacent ends of the cutter pins, and adapted to secure them in operative position.

In testimony whereof, we hereunto affix our signatures, this the 26th day of May, A. D., 1925.

FLOYD L. SCOTT.
RALPH NEUHAUS.
